REVERSIBLE DRIVE

Louis E. Misippo, Boulder Creek, Calif.

Application January 18, 1946, Serial No. 642,096

1 Claim. (Cl. 74—66)

1

My invention relates to drives, and more particularly to a reversible drive for ship propellers or the like, though it is to be understood that the invention is of general utility.

Among the objects of my invention are:

(1) To provide a novel and improved reversible drive;

(2) To provide a novel and improved reversible drive in which there is a complete absence of gears;

(3) To provide a novel and improved reversible drive having quick response in its reversing function;

(4) To provide a novel and improved reversible drive wherein the change in direction of drive is accomplished in a smooth and efficient manner;

(5) To provide a novel and improved reversible drive of rugged design and construction.

Additional objects of my invention will be brought out in the following description of a preferred embodiment of the same, taken in conjunction with the accompanying drawings wherein—

Figure 1 is a plan view of a preferred embodiment of my invention, partly broken away to disclose some of the internal elements;

Figure 2 is an elevational view, partly in section, of the device of Figure 1;

Figure 3 embodies a series of diagrams depicting a complete revolution of the drive shaft of the device, in each of its adjusted positions representing forward, neutral and reverse drives.

In general, the invention in its preferred embodiment, includes a drive shaft and a driven shaft, each terminating in a crank. Supported by and between these cranks, on swivel connections, is a connecting link which slidably receives a cross-bar, and this cross-bar in turn, is selectively connectable through a neutral position, to either the drive shaft or to a fixed anchorage in the form of a sleeve surrounding the driven shaft. The selected position of the cross-bar, in cooperation with the swivel link connection between the drive and driven shafts, determines the operation of the device.

Referring to the drawings for a more detailed description of the preferred embodiment, a drive shaft 1 emerges from a prime mover, such as an electric motor 3, and is supported in a bearing 4 carried in a bearing housing 5 mounted on a bracket 7, while a driven shaft 9 which leads to the load (not shown but which could be a ship's propeller) is similarly supported in a bearing 10 likewise carried in a bearing housing 11 mounted on a bracket 13.

The facing ends of these shafts, each carry a crank in the form of a transverse arm 15 having a pin 17 extending parallel to the axis of its shaft and in the direction of the other.

2

Supported by and between these cranks by swivel connections, is a connecting link 19. This link is formed with forked ends in each of which is mounted a swivel block 21 having an axial bore to slidably receive the pin 17 of the adjacent crank.

A cross-bar 23 slidably receivable in a transverse bore through the link 19, is adapted through suitable clutch means to be selectively connected to either the drive shaft 1 or a fixed anchorage on the driven shaft 9 in the form of a collar 24 which may be an integral extension of the bearing 10.

Such clutch means includes a cylinder 25 surrounding the cranks and the swivel mounted connecting link supported between them, with the cross-bar lying diametrically of the cylinder and having its ends embedded in the wall thereof.

The cylinder at each end is sealed by a fixed end plate 27 mounted on one of the aforementioned shafts and capable of rotation thereon. Each fixed end plate functions as a fixed clutch plate, and is preferably formed with a frusto-conical depression having its axis coincident with the axis of the shaft that passes through it.

A shiftable clutch element in the form of a frusto-conical disc 29 to provide a complementary fit with an end plate 27 of the cylinder, is slidably mounted on each shaft adjacent an end of the cylinder, and provided with a tail sleeve 31. The drive shaft disc and its associated tail sleeve is keyed to the drive shaft in a manner, as by a key 33, to preclude rotation of the disc around the shaft, without impairing its ability to slide thereon. The driven shaft disc, on the other hand, has its tail sleeve overlapping the collar 24 to which it is slidably keyed as by a key 34.

Engagement of one or the other of the clutch discs with its associated clutch plate is manually controlled through a shift mechanism, the shifting of the discs being simultaneous to preclude any possibility of these discs engaging at the same time. Toward this end, each tail sleeve is formed with a peripheral groove 35 to receive a split shift collar 37.

Each shift collar is pivotally secured in a yoke 39 which in turn has its shank 41 pivotally secured to an arm 43 mounted at the base of each of the bearing brackets 7 and 13. A link 45 pivotally interconnecting the two yokes at an intermediate point on their shanks, provides for simultaneous shifting of the two clutch discs 29 in a common direction, whereby only one of the clutch discs may engage at a time. The shift is accomplished manually through the expediency of a handle 47 extending upwardly from and preferably formed integrally with one of the yokes.

A forward throw of the handle will bring the drive shaft 1 into positive drive engagement with the cylinder 25 and effect a drive connection to

the cross-bar 23. Under these circumstances, the cylinder 25 and link 19 may be considered locked into a unitary assembly, precluding relative sliding movement of the link on the cross-bar 23. In this condition, the drive shaft drives directly through to the driven shaft by way of the crank on the driven shaft, causing the driven shaft to rotate in the same direction as the drive shaft, which direction, for convenience, will be considered the forward direction.

Upon throwing the handle to its extreme position in the opposite direction, the drive shaft disc will disengage, followed by engagement between the driven shaft disc and its associated clutch plate.

With the driven shaft clutch disc in engagement with its clutch plate, the cylinder and consequently the cross-bar is restrained against movement, it being recalled that the driven shaft clutch disc is keyed to the fixed collar 24. With such conditions existing, the drive shaft crank operating on the link, causes the link to execute a compound movement involving a reciprocating movement on the cross-bar and a simultaneous oscillatory movement on the cross-bar axis. This compound movement of the link is converted to a rotational movement of the crank on the driven shaft and in a direction opposite to that of the drive shaft crank. Thus the driven shaft will rotate in reverse.

Between the two extreme positions of the clutch shift handle, a condition exists wherein neither of the clutch discs is in engagement with its associated clutch plate. In response to the driving force of the drive shaft crank, the link is caused to undergo the same compound movement as previously described, namely a reciprocating movement on the cross-bar while simultaneously oscillating on the axis of the cross-bar, but the movement becomes further complicated by the fact that the cylinder, being free of restraint, is capable of rotation and will cause simultaneous rotation of the cross-bar with it, with the result that the complex movement of the connecting link will be about a fixed point coinciding with the position of the pin on the crank of the driven shaft in the position it happens to be in when the clutch discs are freed of any engagement with their associated clutch plates.

Under these conditions and assuming a minimum of friction, no rotating component of force is transmitted to the driven shaft. Consequently the driven shaft will, in effect, be disconnected from the drive shaft. Thus with both clutch discs out of engagement, the device is in neutral condition insofar as the driven shaft is concerned.

The changeover from one mode of operation to another, though quickly effected, is nevertheless accomplished smoothly and efficiently, attributable largely to the fact that the enclosed working parts, through which the drive forces are applied to the driven shaft, are always in mesh.

Figure 3, by means of series of sketches, illustrates the various movements described as occurring under the conditions determined by the forward, neutral and reverse adjustments of the clutch mechanism.

For purposes of illustration and convenience, these diagrams assume a starting position as illustrated in Figs. 3a and 3b, which correspond to Figs. 1 and 2. The series c, c₁ and c₂ are plan views for each quarter revolution of the drive shaft with the clutch adjusted for forward rotation of the driven shaft, while series d, d₁ and d₂ represent corresponding views in elevation.

Similarly, series e, e₁ and e₂ represent plan views for each quarter revolution of the drive shaft with the clutch mechanism adjusted for neutral operation, while series f, f₁ and f₂ are corresponding views in elevation.

Likewise, series g, g₁ and g₂ are plan views for each quarter revolution of the drive shaft with the clutch mechanism adjusted for reverse motion of the driven shaft, while series h, h₁ and h₂ are corresponding views in elevation.

Aside from the fact that the sealed cylinder functions as part of the clutch mechanism, it protects the enclosed elements against dust and dirt, and can be utilized as an oil reservoir for assuring continuous and automatic lubrication of such elements.

While I have disclosed my invention in its preferred form, the same is subject to change and alteration without departing from the underlying principles involved, and I accordingly do not desire to be limited in my protection to the specific details illustrated and described, except as may be necessitated by the appended claim.

I claim:

A reversible drive comprising a drive shaft; a driven shaft; a crank on the end of each of said shafts, each crank including an arm normal to its shaft and a pin extending from said arm parallel to such shaft; a link including a swivel block at each end, said link being supported between said cranks with each of said swivel blocks slidably mounted on one of said pins; a cross-bar slidably receivable by said link in a direction normal thereto; a fixed anchorage in the form of a fixed collar surrounding said driven shaft, and clutch means for selectively connecting said cross-bar in drive connection with either said drive shaft or said fixed collar, said clutch means including a cylinder enclosing said cranks and link, with said cross-bar disposed diametrically of said cylinder and having its ends anchored to the wall thereof, said cylinder having end plates constituting fixed clutch plates, a disc slidably mounted on each of said shafts with the drive shaft disc keyed thereto for rotation therewith, the driven shaft disc keyed to said fixed collar, and shift means for selectively shifting said discs into and out of engagement with their associated clutch plates.

LOUIS E. MISIPPO.
